(57) **CLAIM**

The ornamental design for a display screen or portion thereof with graphical user interface as shown and described.

DESCRIPTION

The FIGURE is a front view of a display screen or portion thereof with graphical user interface showing our new design.

The dash-dash broken lines shown in the figure are for illustrative purposes only and form no part of the claimed design.

The dash-dot broken lines show portions of the display screen that form no part of the claimed design.

1 Claim, 1 Drawing Sheet
